(57) CLAIM

The ornamental design for a protective case for mobile phone, as shown and described.

DESCRIPTION

FIG. 1 is a rear view of a protective case for mobile phone in accordance with the present invention.

FIG. 2 is a front view thereof.

FIG. 3 is a left end view thereof.

FIG. 4 is a right end view thereof.

FIG. 5 is an enlarged bottom view thereof.

FIG. 6 is an enlarged top view thereof.

FIG. 7 is a perspective view showing an open position thereof.

FIG. 8 is another perspective view showing an open position thereof.

FIG. 9 is an enlarged perspective view of a protective case for mobile phone in use with a mobile phone thereof.

FIG. 10 is another enlarged perspective view of a protective case for mobile phone in use with a mobile phone thereof.

FIG. 11 is another enlarged perspective view of a protective case for mobile phone in use with a mobile phone thereof.

FIG. 12 is another enlarged perspective view of a protective case for mobile phone in use with a mobile phone thereof; and,

FIG. 13 is another enlarged perspective view of a protective case for mobile phone in use with a mobile phone thereof. The broken lines in FIGS. 9–13 showing viewable portions of a mobile phone are for the purpose of depicting environment only that form no part of the claims.
